UNITED STATES PATENT OFFICE.

FREDERICK S. CHASE, OF WATERBURY, CONNECTICUT, ASSIGNOR TO THE
WATERBURY MANUFACTURING COMPANY, OF SAME PLACE.

DESIGN FOR AN OIL-CAN.

SPECIFICATION forming part of Design No. 25,946, dated August 18, 1896.

Application filed July 20, 1896. Serial No. 599,975. Term of patent 7 years.

To all whom it may concern:

Be it known that I, FREDERICK S. CHASE, of Waterbury, in the county of New Haven and State of Connecticut, have invented a new 5 Design for Oil-Cans; and I do hereby declare the following, when taken in connection with the accompanying drawing and the letters of reference marked thereon, to be a full, clear, and exact description of the same, and which 10 said drawing constitutes part of this specification, and represents a perspective view of an oil-can embodying my design.

This invention relates to a design for an oil-can, and the design consists in the ornamentation of the can, as shown in the accompanying illustration and hereinafter described.

My newly-designed oil-can consists of a cylindrical body A, having a series of trans- 15 versely-arranged circumferential corruga-

tions or bands extending throughout its main portion. The upper end of the said body has a circumferential beveled band B, above which is a tapering radially-corrugated neck C, the contracted upper end of which is overhung 25 by the spout-flange D, which receives the cylindrical spout-cap E, all as shown in the accompanying illustration.

I claim—

The design for an oil-can as shown in the 30 accompanying illustration and herein described.

In testimony whereof I have signed this specification in the presence of two subscribing witnesses.

FREDERICK S. CHASE.
